UNITED STATES PATENT OFFICE.

HERMAN A. HANSON, OF CHICAGO, ILLINOIS.

BRUSH.

1,088,275.

Specification of Letters Patent. Patented Feb. 24, 1914.

Application filed September 24, 1913. Serial No. 791,473.

To all whom it may concern:

Be it known that I, HERMAN A. HANSON, a citizen of the United States, and a resident of the city of Chicago, county of Cook, 5 and State of Illinois, have invented certain new and useful Improvements in Brushes, of which the following is a specification.

My invention relates to brushes and more specifically to that class thereof wherein a 10 moistener is provided for moistening the bristles of the brush in order to prevent the dust being thrown into the atmosphere during the use of the brush such as is the case with brushes not equipped with moistening 15 means.

The object of my invention is the production of a brush of the character mentioned which will be of durable and economical construction and efficient in use.

20 Other objects will appear hereinafter.

The invention consists in the combinations and arrangements of parts hereinafter described and claimed.

The invention will be best understood by 25 reference to the accompanying drawing forming a part of this specification, and in which—

Figure 1 is a perspective view of a brush embodying my invention, Fig. 2 is a vertical 30 longitudinal section thereof, and Fig. 3 is a vertical transverse section taken on substantially line $x-x$ of Fig. 2.

The preferred form of construction as 35 illustrated in the drawing comprises a rectangular brush back 1 at the under side of which are provided bristles 2 which are secured in the former in the usual manner. A handle 3 is provided which is secured in the back 1 in the usual manner. Mounted upon 40 the upper side of said back 1 is an elongated longitudinally extending liquid tank 4 secured in position by means of loops 5 which embrace said tank as shown in the several views. Provided at the upper side of said 45 tank intermediate the ends thereof is a filling plug 6 through which access may be gained to the interior of said tank for filling or emptying the same. The ends of tank 4 are closed by removable closure plugs 7

50 formed preferably of cork. The end portions of said tank at the under sides thereof are provided with elongated longitudinally extending slots 8 which register with corresponding slots 9 provided in the back 1. Arranged at the under side of the back 1 is a 55 longitudinally extending strip 10 of absorb-

ent material which extends longitudinally of said back and preferably medially of the longitudinal edges thereof. The central portion of said strip is secured by means of 60 staples or other suitable fastening devices 11 to the under side of said back, the strip depending therefrom to a position between the bristles 2 in the manner illustrated. The respective ends of said strip are passed upwardly through the slots 9 and 8 terminating in the interior of the tank as clearly shown in Figs. 2 and 3. Said ends are secured in position by the closure 7, the former being clamped between said closures and the 70 bottoms or inner ends of the slots 8.

With the arrangement disclosed it will be seen that the liquid contained in the tank 4 will be absorbed by the ends of the strip 9 passing downwardly therethrough into the 75 body of the strip whence said liquid will be transferred to the brush bristles which are pressed into contact with said strip through flexing during operation of the brush. With this arrangement it will be seen that a self-feeding arrangement is provided, the liquid 80 passing automatically from the tank 4 through the ends of the absorbent strip into the body of the latter and thence to the brush bristles. By adjusting the positions of the closures 7 in the ends of the tank the 85 clamping of the ends of the absorbent strip may be increased or decreased and thus the flow of liquid from the tank through said strip ends regulated, it being clear that if the closures are moved outwardly in order 90 to relax the clamping of said strip ends a greater amount of liquid will be permitted to pass therethrough and, conversely if said closures are pressed inwardly to increase the 95 pressure or clamping of said strip ends the flow of liquid therethrough will be retarded. Thus closures 7 through their frictional engagement with the ends of the tank which renders said closures longitudinally adjustable in said tank, serve the double function 100 of closures for the tank ends and means of regulating the flow of liquid from the tank to the absorbent strip.

At the ends of the brush back 1 are provided 105 elongated pads 12 which serve primarily to prevent marring of any polished or delicate surface with which the brush may be brought in contact in the use thereof. Said pads 12 also serve to cover the outer ends of slots 9 110 as shown so as to produce a brush which is of neat and finished appearance.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claim.

Having described my invention what I claim as new and desire to secure by Letters Patent is:

A brush comprising a back having a slot 15 in each end; bristles provided at the under side of said back; a liquid tank secured to the upper side of said back provided with

elongated slots in the ends of said tank registering with slots in said back; a strip of absorbent material interposed between said bristles and having its ends extending upwardly and engaging the slots in said back and tank; and removable closures in the ends of said tank serving to secure the ends of said strips in position in said slots and regulate the flow of liquid from said tank, substantially as described.

In testimony whereof I have signed my name to this specification in the presence of two subscribing witnesses.

HERMAN A. HANSON.
